UNITED STATES PATENT OFFICE

GEORGES GRANDJEAN, OF LES FORGETS, ISLE ADAM, FRANCE, ASSIGNOR TO ISOTHERMOS CORPORATION OF AMERICA, OF NEW YORK, N. Y., A CORPORATION OF DELAWARE

AUTOMATIC LUBRICATING JOURNAL BOX

Application filed February 9, 1929, Serial No. 338,861, and in Switzerland November 14, 1928.

The invention relates to automatic lubricating journal boxes, such as employed in railway cars and vehicles, in which the journal box involves a well or receptacle containing a body of oil into which a paddle or blade attached to the end of the journal dips and collects a portion of the oil which is delivered to the bearing, either by gravity or by centrifugal force, according to the speed of rotation of the journal and the blade or paddle attached thereto; the journal box, in accordance with the present invention, including means for separating solid impurities from the oil before the latter is returned to the well, so as to insure none but pure oil for delivery to the bearing, the separating means preferably being in the form of a baffled decantation device located in the bottom of the journal box through which the oil dripping from the bearing and the journal is caused to flow in a zigzag course, so that all solid material will settle out of the oil before the latter is redelivered to the well.

Various forms of the invention are illustrated in the accompanying drawings, in which:

Fig. 1 is a vertical half section in which the decantation device is formed as a separate unit.

Fig. 2 is a vertical section on line 2—2 of Fig. 1.

Fig. 3 is a horizontal section on line 3—3 of Fig. 1.

Fig. 4 is a view similar to Fig. 1 showing a modified type of removable decanter.

Fig. 5 is a detail plan view of the decanter.

Fig. 6 is a longitudinal section through a further modification of the decanter shown in Fig. 4.

Fig. 7 is a similar view showing a further modification.

It has been found that, in the operation of automatically lubricated journal boxes, continued use will cause the oil to entrain solid particles which may be detached from the walls of the box or may be abraded from the journal or the bearing, which, if not removed, will be returned with the lubricant to the bearing, resulting in damage to the wearing surfaces and not infrequently causing dan-

gerous heating of the parts. As indicated, the present invention is designed to obviate these difficulties and dangers by causing separation of the solid materials from the oil before the latter is returned to the well where it is picked up by the distributing paddle or blade for delivery to the bearing.

Referring to Fig. 1, 10 indicates the journal box, which is of the usual type employed with automatic lubricating means, such, for example, as that disclosed in the prior Eveno Patent No. 1,617,205, and comprising a paddle or blade 20 attached to the end of the journal section 21 of the axle, the said journal engaging with the usual bearing (not shown) seated on the under face of the top of the box and provided with distributing channels communicating with the journal. In operation, the ends of the paddle traverse the body of oil contained in the wall or reservoir 19 at the bottom of the box and pick up a portion of the oil and, according to the speed of rotation of the axle, either allows the oil to drip onto the top of the bearing, or else throws it against the top of the box by centrifugal force from whence it flows onto the top of the bearing.

In the embodiment shown in Fig. 1, the top of the decantation apparatus constitutes the inclined flection plate 25 which receives the drippings from the journal and bearing and delivers the same to the inlet end of the decantation apparatus. In other respects, the construction is the same as that shown in the preceding figures. As indicated in this figure, a settling well or chamber 26 may be provided in the bottom of the box adjacent the inlet end of the decantation device for receiving the heavier particles or impurities, in which case the oil passing through the decantation device will retain only the lighter particles or impurities.

In Figs. 2, 3 and 4, there is shown a modification in which the decantation or separating device is formed as a separate unit adapted to be applied to and removed from the journal box as conditions may require, the device comprising a casing 27 which is fitted between the side walls of the journal box and held in position by two cross par-

titions II', II', which are provided with perforations 28, 28' registering with inlet and discharge openings in the ends of the casing 27. The interior of the casing 27 is provided with vertically alternating baffle plates extending preferably from one side wall to the other of the casing, so that the casing includes a series of decantation pockets. The oil dripping from the bearings falls upon the inclined plate 23, is delivered thereby to the rear end of the journal box, passes through the opening 28 in the partition II' enters the decantation apparatus and traverses the different decantation pockets in said apparatus and is ultimately discharged from the opening 28', into the well 19, after being freed from all solid matter in its passage through the separator.

20 Figs. 4 and 5 show a modification of the removable decantation or separating apparatus, the latter being here shown as a casing 27' having one end provided with a series of settling cells formed by longitudinal and transverse partitions 52 and 53. The top 55 of the casing is inclined to deliver the oil dripping from the journal and bearing into the cellular compartments of the casing to facilitate the settling of the heavier material and the retention thereof in the cells. Similarly, the oil delivered by the check ring 24, usually employed in connection with devices of this character, falls upon an inclined section 50 of the journal box and drips off the latter into the said cellular structure at the end of the decantation apparatus. The oil overflowing the top edges of the partitions 52-53 forming the cells enters the decantation apparatus 40 where it is forced in a zigzag path over and under the baffles and is ultimately discharged through the opening in the end of the separator into the well 19.

As shown in Fig. 6, the removable purifier or decantation device is given a form to facilitate its ready application to and removal from the journal box, by providing the rear end thereof with a curved section 57, which also serves to retain the oil in the device when the latter is tipped in withdrawing the same from the journal box.

In order to facilitate the flow of the oil through the decanter or purifying device, the latter may be given the form shown in Fig. 7, with the bottom inclined to the horizontal to fit a correspondingly arranged bottom of the journal box, the baffles 58 and 59 extending to different heights and depths and extending from one side wall to the other of the casing, so that the casing includes a series of decantation pockets in stepped relation.

In each of the removable purifiers or separators, the top thereof may be provided 65 with a suitable handle or bail 56 to facili-

tate the application and removal of the device.

In the particular forms of the device in which the decantation apparatus involving the vertically and horizontally alternating baffles are formed as integral parts of the box, it will be understood that any excessive accumulation of foreign material in the separator may be removed by washing the entire contents of the journal box out through the settling well 26 at the rear portion thereof, which is usually provided with a discharge valve for such purpose. In all cases where the decantation apparatus is formed as a separate removable unit, however, when it is found necessary to clean out the accumulated solid matter, it is necessary only to remove the purifying apparatus through the usual opening in the outer end of the journal box and replace the same by a new one.

What I claim is:

1. An oil purifying device for journal boxes comprising a casing separate from the box adapted to be inserted into and removed from the latter, said casing having oil baffle plates therein and being provided at one point with an oil inlet opening and at another point with an oil outlet opening.

2. An oil purifying device for journal boxes comprising a casing separate from the box adapted to be inserted into and removed from the latter, said casing being inclusive of side, end, top and bottom walls, and baffle plates within said casing providing a tortuous passage from end to end thereof, said casing being provided with an oil inlet opening communicating with one end of said passage and with an oil outlet opening communicating with the other end of said passage.

3. In combination, a journal box adapted to contain a lubricant, an axle journaled in said box, means for delivering lubricant from said box to said axle, a pair of transverse partitions cooperating with the sides and bottom of the box to provide a seat to receive and hold a lubricant purifying device, and a lubricant purifying device separate from said box removably engageable with said seat, said partitions having openings formed therethrough and said purifying device having inlet and outlet openings therein disposed to register with the openings in said partitions, respectively, when the purifying device is operatively engaged with its aforesaid seat.

4. An oil purifying device for journal boxes comprising a casing separate from the box adapted to be inserted into and removed from the latter, said casing being inclusive of side, end, top and bottom walls, and baffle plates within said casing providing a tortuous passage from end to end thereof, said casing being provided with an oil inlet open-

ing communicating with one end of said passage and with an oil outlet opening communicating with the other end of said passage, alternate of said baffles extending upwardly from the bottom of the casing and terminating at their upper ends in spaced relation to the top of the casing to provide a series of separate oil pockets, and the other of said baffles extending downwardly from the top of the casing into said pockets in spaced relation to said first mentioned baffles and terminating at their lower ends in spaced relation to the bottom of the casing.

5. In a journal box, the combination with the bottom of the box having a well formed therein, of means on the bottom of the box adjacent the well for holding an oil purifying device, and a receptacle having oil inlet and outlet openings and sediment traps therein 10 and removably engaged with said means.

6. An oil purifying device for journal boxes, comprising a casing separate from the box and adapted to be inserted into and removed from the latter, said casing having 15 sediment traps therein and also provided with oil inlet and outlet openings.

7. In a journal box, the combination with the bottom of the box having a well therein, of a receptacle having an oil inlet opening 20 and an oil outlet opening, sediment traps in the receptacle, and means for holding said receptacle in the journal box.

In testimony whereof I affix my signature.
GEORGES GRANDJEAN.
